UNITED STATES PATENT OFFICE

HUBERT A. MYERS, OF TOLEDO, OHIO

TOY

Application filed November 5, 1929. Serial No. 405,021.

My invention has for its object to provide a toy which is so constructed that it may be caused to rise by winding on a string, used to support the toy, by the speed or momentum of rotation created by causing it to rotate in an unwinding movement, while allowing it to descend. The inertia of the mass causes it to wind and rise along the string that supports it. The invention particularly relates to the formation of the body of the toy so that a large proportion of the mass will be located in proximity to the axis of rotation and a smaller portion of the mass will be formed into closely positioned flanges having relatively large diameters as compared to the central and larger portion of the mass of the toy. The invention also provides, in connection with such a toy, a means for protecting the body of the toy from the friction of the cord in its rotation, whereby the body of the toy may be formed of a relatively soft material, if desired, such as a confection, namely, of gum or candy.

The invention may be contained in toys that vary in their details of construction and, to illustrate a practical application of the invention, I have selected a toy embodying the invention, and shall describe it herein-after. The toy selected for purposes of illustration is shown in the accompanying drawings.

Fig. 1 is a perspective view of the toy. Fig. 2 is a view of a section of the toy through its axle. Fig. 3 is a view of a section of the toy taken on the plane of the axis of its axle.

The toy consists of two circular parts 1 and 2, and an axle 3. The parts 1 and 2 may have, relative to the axle 3, a considerable mass and is preferably formed of any moldable material, such as paraffin gum, or candy, or other confection, or other plastic. The axle 3 is formed of wood, which is secured in the parts 1 and 2 by having its ends embedded therein. The parts 1 and 2 are secured to the pin or axle 3 so as to locate their inner faces, which are plane surfaces, in close parallel relation. The outer surfaces of the toy are formed to provide a large mass or weight in the central portion of the members 1 and 2, such as the portion 4, forming thereby flanges

5 that taper in the cross section of the toy, as indicated in Fig. 3. The outer surfaces of each of the members 1 and 2 have a curved truncated surface 6 which slopes from the inner plane surface and terminates at the plane surface 7 that defines the hub of each member. 55

A cord 8 is connected to the axle or pin 3 and is wound thereon. When, therefore, the free end of the cord 8 is supported and the toy is allowed to fall, its weight will cause the rotation of the toy. When the toy reaches the end of the string, its inertia and rotation will cause it to wind up and rise on the string. 60

In order to prevent frictional wearing of the inner plane surfaces 10 of the members 1 and 2, they are covered with paper discs 11, which protect the members 1 and 2, and greatly extend the life of the toy where it is formed of a semi-plastic material. The paper discs may be secured to the surface by moistening the material or by application of the discs while the material is still soft or yieldable. 70

I claim:

In a toy, a pair of members formed of fragile palatable material, the members having lateral surfaces located in proximity to each other and in opposed relation to each other, the lateral surfaces having relative tough discs of thin sheet material located thereon, an axle member having its ends embedded within the said members, and a cord attached to the axle whereby the cord may be wound on the axle between the discs of relative tough material to cause the inertia of the members to raise the toy and wind up the string when in rotation and the fragile palatable material is protected from the rubbing of the cord and the cord is protected from impregnation by the fragile material. 80 85 90

In witness whereof I have hereunto signed my name to this specification.

HUBERT A. MYERS.
